(57) **CLAIM**

The ornamental design for a folding wireless charger, as shown and described.

DESCRIPTION

FIG. 1 is a front perspective view of a folding wireless charger, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the folding wireless charger, shown in an unfolded state;

FIG. 10 is a front view thereof of its unfolded state;

FIG. 11 is a rear view thereof of its unfolded state;

FIG. 12 is a left side view thereof of its unfolded state;

FIG. 13 is a right side view thereof of its unfolded state;

FIG. 14 is a top view thereof of its unfolded state;

FIG. 15 is a bottom view thereof of its unfolded state;

FIG. 16 is a bottom view of the folding wireless charger, shown in a closed state; and,

FIG. 17 is a top view thereof of its closed state.

The broken lines in the drawings illustrate the portions of the folding wireless charger, which form no part of the claimed design.

1 Claim, 17 Drawing Sheets
